UNITED STATES PATENT OFFICE

2,560,457

SAFETY ESCAPE LADDER

Edwin W. Litten, Pittsburgh, Pa.

Application January 31, 1948, Serial No. 5,582

1 Claim. (Cl. 228—2)

1

This invention relates to a portable fire escape in the form of a flexible ladder and, in particular, to a ladder secured to a chair having a tubular frame adapted to be quickly disposed over a window sill so as to afford a safe and secure anchorage therefor while the ladder is in use. The invention also includes improved features in the ladder itself.

Flexible ladders have been proposed heretofore as fire escapes but those with which I am familiar are difficult to place in position for use and are bulky and cumbersome to stow away when not in use.

The use of chairs as an anchorage for such ladders has also been suggested but only straight, high-backed chairs adapted to engage the window sill and the lower rail of the sash when raised. When used in this manner, the chair back blocks the window and makes exit therefrom extremely difficult.

I have invented a novel combination comprising a flexible escape ladder secured to a tubular frame chair of such construction that it is adapted to be placed with its legs extending across a window sill. When the chair is so placed, the base will extend downwardly along the outside of the wall and the seat rails will extend downwardly along the inside of the wall, thereby affording a highly effective anchorage and leaving the window unobstructed.

A further novel feature of the invention is the provision for securing the rungs of the ladder to the flexible side members such as chains.

A complete understanding of the invention may be obtained from the following detailed description which refers to the accompanying drawings illustrating a present preferred embodiment.

In the drawing wherein like numerals of reference designate corresponding parts throughout the several views,

Figure 1 is an isometric view showing the invention in position for use as a fire escape.

Figure 2 is a side elevation showing the invention with the ladder stowed under the chair so as to permit normal use of the latter.

Figure 3 is an enlarged partial elevation showing the ladder construction and the attachment thereof to the chair.

Figure 4 is a detail perspective view showing the means for securing the rungs to the side chains, and

Figure 5 is a perspective view of one end of a rung showing an intermediate stage of fabrication of the ladder.

2

Referring in detail to the drawings, my invention comprises a flexible ladder 10 secured to a tubular frame chair 11. The ladder is composed of spaced side chains 12 and 13 with rungs 14 extending therebetween. The rungs are preferably short lengths of pipe of suitable size. The chair 11 is of a known type and comprises a continuous frame 15 of metal tube including a base 16, front legs 17, seat rails 18 and a back 19, with a seat proper 20 secured to the rails 18 and a panel 21 to the back 19. There are no back legs, the space between the base and seat rails being open at the back. While the various portions of the frame have been separately designated, it will be understood that they are ordinarily composed of a single length of tube bent to shape and having its ends welded together to constitute a continuous, one piece structure.

20 The chains 12 and 13 may be of any suitable form, but I have selected the chain as best shown in Figure 4, which is obtainable in any hardware store. The chains are secured to the chair frame in any convenient manner, preferably 25 they are secured to the front legs 17 adjacent the base 16 by split clamping collars 22 having through bolts 23 passing through the collar members and the uppermost links of the chains. The rungs 14 are secured to the chains by inner 30 tongues 24 and outer tongues 25. These tongues are formed by slotting the ends of the pipe lengths to be used as rungs, as indicated at 26 in Figure 5. After slotting, two opposite portions of the pipe wall between the slots are bent 35 outwardly to form radial tongues 24 as clearly shown in Figure 4.

The ends of the pipe lengths are then inserted through the chain links and the remaining wall portions thereof bent outwardly to form tongues 40 25. In the illustrated embodiment, the tongues 24 extend lengthwise of the chains and serve to maintain the chain properly apart. The tongues 26 extend transversely of the chains and serve to prevent detachment of the chains from the 45 rungs. After the rungs have been assembled with the chains as described they are permanently secured in assembled position and it will be impossible for the chains to become detached from the rungs if the rungs are made of proper length.

When the device is not in use as a fire escape, the chain may be readily stowed under the seat of the chair as shown in Figure 2. For the sake of appearance, it may be placed in a bag or other container of suitable material designed for 55 quick removal, so the ladder will be immediately

available when needed but still not unsightly in the meantime.

In case of fire, it is only necessary to open a window, remove any covering from the ladder, and place the chair with its legs extending across the window sill as shown in Figure 1 whereupon the ladder falls by its own weight and remains securely suspended and available for immediate descent. As shown, the base 16 of the frame extends downwardly along the outside of the wall W below the sill S while the seat rails 18 extend downwardly along the inside of the wall. When the chair is in this position, the back panel 21 extends substantially horizontally below the window sill on the inside of the building and thus serves admirably as a step by which the exit of the occupants through the window is greatly facilitated.

When the chair has been suspended as described, the tongues 25 adjacent the wall serve to space the rungs therefrom, thereby insuring a safe, secure footing for the user as the descent is made from one rung to the next. The tongues 25 are held in transverse relation to the chains by the engagement of the tongues 24 with the links through which the tongues 25 extend.

It will be apparent that the invention has many advantages over safety escape ladders as known heretofore. The tubular frame of the chair provides an anchorage which can easily be made fast by anyone, the chair and ladder being of a combined weight small enough to permit lifting by a frail adult as well as a child. The placement of the device in position for escape is simplicity itself requiring no clamping or other fastening procedure. At the same time, no permanent attachment to the building is necessary and the device is always freely portable so it may be taken from room to room or from house to house. In addition, the chair is always available for seating purposes when not needed for escape.

The construction of the device is simple and inexpensive and the cost of the chair is not great considering the fact that it serves a dual purpose.

Although I have illustrated and described only a preferred embodiment of the invention, it will be understood that changes may be made in the details and arrangement thereof without departing from the spirit of the invention or the scope of the appended claim.

I claim:

A portable fire escape comprising in combination a chair having a tubular frame including a base, two front legs extending upwardly therefrom, seat rails extending horizontally from said legs, said base, legs and seat rails forming a substantially U-shaped structure, a back extending upwardly substantially normal to the ends of the seat rails remote from the legs, said seat rails and base being adapted to engage opposite sides of a wall beneath a window sill with the legs extending across the sill, fastening means on the legs adjacent the base for holding a ladder spaced from the window sill, a flexible ladder attached to said means and adapted to be suspended alongside the wall of a building in spaced apart relation thereto, and storage facilities for said ladder between said rails and base.

EDWIN W. LITTEN.
